UNITED STATES PATENT OFFICE.

FRANZ YOKEL, OF MERIDEN, CONNECTICUT, ASSIGNOR TO THE MERIDEN BRONZE COMPANY, OF SAME PLACE.

DESIGN FOR A TABLE-TOP.

SPECIFICATION forming part of Design No. 21,750, dated August 2, 1892.

Application filed June 29, 1892. Serial No. 438,466. Term of patent 3½ years.

To all whom it may concern:

Be it known that I, FRANZ YOKEL, of Meriden, in the county of New Haven and State of Connecticut, have invented a new Design 5 for a Table-Top; and I do hereby declare the following, when taken in connection with accompanying drawing and the letters of reference marked thereon, to be a full, clear, and exact description of the same, and which said drawing constitutes part of this specification, and represents a top or face view, the ornamentation represented on one-fourth only, the remaining three-fourths being each a duplicate thereof.

15 This invention relates to a design for an ornamental table; and it consists in the configuration and ornamentation as shown in the accompanying illustration. In general outline the table is square, with an ornamental 20 projection at each angle. From a central rose in the center a double scrollwork springs toward each of the angles, and each angular

projection is bordered by the representation of scrolls or roccoco-work, which extends onto the adjacent sides, and between the scrolls 25 which spring from the angles on each side is the representation of a pair of scrolls substantially parallel with the respective sides, and the scrollwork or roccoco-work is represented as filled in with lacework. Around the 30 edge of the table is the representation of leaf-work, as shown in the accompanying illustration.

I claim—

The design for a table-top, as herein shown 35 and described.

In testimony whereof I have signed this specification in the presence of two subscribing witnesses.

FRANZ YOKEL.
